[57] **CLAIM**

The ornamental design for the hand prosthesis, as shown and described.

DESCRIPTION

FIG. 1 is a perspective view of the hand prosthesis, showing my new design in a closed “pinching” position;

FIG. 2 is a front view thereof;

FIG. 3 is a right side view thereof;

FIG. 4 is a rear side view thereof;

FIG. 5 is a left side view thereof;

FIG. 6 is a bottom plan view thereof;

FIG. 7 is a top plan view thereof; and,

FIG. 8 is a perspective view of the hand prosthesis showing my new design in an open position.

The broken line showing of structural features in FIG. 6 is for illustrative purposes only and forms no part of the claimed design.
